Primary Examiner — Selina Sikder(74) *Attorney, Agent, or Firm* — McAndrews, Held & Malloy, Ltd.(57) **CLAIM**

The ornamental design for a touch-less swipe controller, as shown and described.

DESCRIPTION

FIG. 1 is a top front perspective view of a touch-less swipe controller showing my new design;

FIG. 2 is a front view thereof;

FIG. 3 is a back view thereof;

FIG. 4 is a left side view thereof;

FIG. 5 is a right side view thereof;

FIG. 6 is a top view thereof; and,

FIG. 7 is a bottom view thereof.

The broken lines in the drawings of the touch-less swipe controller or the parts and/or portions thereof are for environmental purposes only and form no part of the claimed design.
